Attorney.

UNITED STATES PATENT OFFICE.

JOHN W. REED, OF CHICAGO, ILLINOIS.

PIANO-BACK.

SPECIFICATION forming part of Letters Patent No. 473,082, dated April 19, 1892.

Application filed March 11, 1891. Serial No. 384,541. (No model.)

To all whom it may concern:

Be it known that I, JOHN W. REED, a citizen of the United States, residing at Chicago, in the county of Cook and State of Illinois, have 5 invented certain new and useful Improvements in Piano-Backs; and I do hereby declare the following to be a full, clear, and exact description of the invention, such as will enable others skilled in the art to which it app-10 pertains to make and use the same.

This invention relates to the frame portion of upright pianos to which the sounding-board, piano-strings, &c., are attached and supported in proper position.

15 The object of the present improvement being to provide an improved arrangement and construction of the framing parts, embodying a strong and rigid form and mode of attachment of the string-plate, a simple and efficient 20 attachment of the sounding-board, whereby extra sounding-surface is attained, and a simple, strong, and durable attachment of the pin-block in position. I attain such object by the construction and arrangement of parts 25 illustrated in the accompanying drawings, in which—

Figure 1 is a front elevation of a portion of the framing part of a piano illustrating my present invention; Fig. 2, a longitudinal section of the same at line $x\ x$, Fig. 1; Fig. 3, a 30 transverse section of the same at line $x'\ x'$, Fig. 1.

Similar numerals of reference indicate like parts in the several views.

35 Referring to the drawings, 1 represents the string-plate, of any usual construction so far as the openings for the passages of the sounding-board bridges and the manner of stiffening and strengthening the margins of such 40 openings are concerned. In the present invention the plate is formed with side and bottom flanges or cheeks 2 and 3 to afford a wide bearing-surface to the side and bottom edges of the frame and furnish substantial 45 means for the outer and marginal wooden frame 4 and 5, that carry the sounding-board 6. In the present invention this marginal frame consists of wooden side and bottom rails of the required size, screwed or bolted 50 to the flanged edges of the string-plate, as shown, the rear faces of such rails projecting backward from the rear of the string-plate

the requisite distance, so as to form a substantial means for the attachment of the sounding-board 6, which is firmly attached 55 thereon by means of the marginal rim 7. At top the side rails 4 of the marginal frame projects up the proper distance to receive and aid in supporting the pin-block or wrest-plank 9 in proper position, the main support for 60 such pin-block, however, being the socket formation at the back of the string-plate, near its top, which is formed by the rearwardly-projecting horizontal rib 10 on the back of the plate, on which the lower edge of the pin-block is supported, the face of such pin-block 65 resting against the back of the string-plate, as shown.

11 are the usual series of holes through the string-plate for the passage of the tuning-pins 70 into the pin-block or wrest-plank.

At its top the sounding-board is supported in front by the horizontal rail 12 on the back of the string-plate and at the back by the top member of the marginal frame or rim 7. With my 75 present improvement the usual heavy wooden piano-back for supporting the sounding-board is dispensed with, and in addition to the great lightness resulting from such omission the present construction admits of the piano being made much thinner and yet preserve its 80 tone and volume, owing to the comparatively larger-sized sounding-board and the omission of the framing timbers back of the same that interfere with and break the sound in a 85 great measure. In the practical construction of the present improvement it is not necessary that the string-plate extend up and wholly cover the pin-block, and such plate may be cut down so as to embrace and cover only the 90 lower front edge of the pin-block without departing from the spirit of my invention.

Having thus fully described my said invention, what I claim as new, and desire to secure by Letters Patent, is—

1. In a frame or back for pianos, the combination of a piano string-plate, an outer marginal wooden frame secured thereto, so as to inclose the same and project rearwardly, and a sounding-board secured to the back of the outer marginal frame, substantially as set forth.

2. In a frame or back for pianos, the combination of the piano string-plate having

marginal cheeks or flanges, the outer marginal wooden frame secured thereto, so as to inclose the same and project rearwardly, and the sounding-board secured to the back of the outer marginal frame, substantially as set forth.

3. In a frame or back for pianos, the combination of the piano string - plate having marginal cheeks or flanges and horizontal rearwardly-projecting flange near its top, the outer marginal wooden frame secured to the marginal flanges of the plate, so as to inclose

the same and project rearwardly, the sounding-board secured to the outer marginal frame, and the pin-block resting upon the horizontal flange of the string-plate, substantially as set forth. 15

In testimony whereof I affix my signature in presence of two witnesses.

JOHN W. REED.

Witnesses:

ROBERT BURNS,
ALANSON H. REED.
